UNITED STATES PATENT OFFICE.

JOHN ARTHUR ANDERSON, OF PORT ARTHUR, ONTARIO, CANADA.

HIGHWAY-CROSSING GATE.

Application filed September 14, 1927. Serial No. 219,438.

The present invention relates to an improved highway crossing gate structure such as is employed at points where public highways, streets, and the like intersect railway tracks, and the purpose of the invention is to provide a means for safeguarding the lives of pedestrians, automobilists, and other occupants of highways and the like.

My principal aim is to generally improve upon inventions of this class by providing one which embodies a new association and organization of elements which cooperate in producing a highly efficient and dependable structure of this type.

The particular details and their arrangement and association, upon which my claims are based, will become more readily apparent from the following description and drawings.

20 In the drawings:—

Figure 1 is a fragmentary perspective view showing the diagrammatic illustration of railway tracks, a highway crossing, the gate, and an approaching train.

Fig. 2 is a fragmentary sectional and elevational view on an enlarged scale showing portions of the trip mechanism, the view being on the right hand side of the track in Fig. 1.

Fig. 3 is a view substantially like Fig. 2 showing the same parts on the opposite side of the track.

Fig. 4 is a vertical section taken approximately upon the plane of the line 4—4 of Fig. 3.

Fig. 5 is an enlarged detail perspective view of the train actuated portion of the trip mechanism.

Fig. 6 is an end view of the gate and a complementary post.

Fig. 7 is a view of an electrical reset device.

Fig. 8 is a perspective view of a plunger forming a part of said device.

Fig. 9 is a top plan view showing the complementary posts and a single gate cooperating therewith.

Referring now to Fig. 1, it will be seen that the reference character 10 designates the gate on the right hand side of the track and 11 designates the gate on the opposite side. Incidentally, these gates are of the same construction and a description of one will suffice for both.

It follows that a pair of posts 12 and 13 constitute the support for the gate. In Figs. 6

and 9, we see the post 12. As here shown, this is provided at its top with a guide slot 14 and provided on its same side and at its bottom with a guide bracket 15. The complementary post 13 shown in Fig. 9, is recessed on one side to accommodate a casing for internal mechanism.

Referring now to Fig. 4, it will be noted that the gate comprises an upper bar 16 and a lower bar 17. A net work is connected to these bars to complete the gate, and this comprises a plurality of horizontal rods 18 connected together by short vertical rods 19 and eyes 20. The rod 17 is slightly shorter than the rod 16 and the last-named rod is provided at its inner end with a circular head 21 having a keeper notch on one side. This head is keyed upon a short operating shaft 22 suitably journaled for rotation in a bearing in the post.

Also as shown in this figure, a latch 23 is pivotally mounted between its ends and has its laterally directed end constructed for reception in the notch. When thus located in the notch, it serves to hold the gate in an elevated or ineffective position. A coiled spring 24 is connected with the latch above the pivot and suitably anchored to the post.

Closely associated with the latch, we find a pair of trip fingers 25 and 26. These are keyed upon a horizontal rock shaft 27. The finger 25 is slightly longer than the finger 26, and it bears against one longitudinal edge of the latch 23, at a point above the pivot for the latch. The other finger engages the latch below the pivot.

Incidentally, the purpose of using the two fingers, is to permit the device to be operated from either side of the track. For example, on the right hand end of the track, one finger serves to trip the latch while on the other side, the other finger operates in the same capacity.

While considering the mechanism here shown, it is desirable to mention a suitable source of light, in the form of a lamp housing, 28, which is mounted on the top of the post and which serves to project a beam of light through a visible signal. These signals are in the form of a green lens 29 and a red lens 30. These lenses are carried by a rockably mounted segment 31, and an operating link 32 connects with this segment, and has eccentric connection with the circular head 21. Thus when the gate is up and in a clear position, the green lens 29 is positioned opposite the source of light to indicate a clear

road; while when the gate drops down by gravity, the link 32 serves to actuate the segment 31 to bring the red lens 30 into play. This enables persons at a distance to ascertain the condition of the track when approaching.

Considering Fig. 9 again, it will be noted that the free end portion of the upper bar 16 is offset as at 33 to operate in the aforesaid guide slot 14 in the post 12. It follows too, 10 that the lower bar 17 operates in the guide bracket 15.

Also as shown in this figure, and in Figs. 2 and 3, a gear 34 is connected with the small shaft 22 and is in mesh with a pinion 35, 15 actuated through the medium of a hand crank 36. These details 34, 35 and 36 constitute a manually operated means for lifting or raising the gates to elevated position.

It is believed that the manually operated 20 reset device just referred to is advantageous for use in outlying districts. However, in the city, I prefer to employ an electrical contrivance or appliance, such as is represented in Fig. 7. In this arrangement, I provide an 25 electro-magnet 37 suitably supported on the upper end of the post 13. This is in electrical connection with rail sections 38, and 39 through the medium of electricity conducting wires 40 and 41, through a suitable source of 30 current such as a battery provided at 42, and a cut-off switch at 43. There is also a switch 44 mounted on the upper end of the magnet and the blade of this switch extends through 35 an elongated slot in the reduced stem portion 45 of the sliding core 46. This core cooperates with the magnet in an obvious manner, and is pivotally connected with the upper bar 16 of the gate.

The circuit is closed by a passing train over 40 the rails 38 and 39 thus energizing the magnet and retracting the core, lifts the gate to elevated position, and as the core slides upwardly, the switch 44 is opened to break the 45 current.

The switch 44 is automatic in operation, 45 while the switch 43 is manually controlled, the last-named switch being employed only when it is desired to bring the electrical contrivance into service. Of course, as the gate 50 is elevated, the latch 23 snaps into the notch in the disk 21 to hold it in such elevated position.

As before stated, the electrical and manual means are employed according to the discretion 55 of the railway company.

Attention is now directed further to the train controlled trip mechanism. As observed in Figs. 2 and 3, the rock shaft 27, 60 which is journaled in appropriate bearings 45 is provided at its opposite ends with crank arms 46. The crank arm in each instance is connected with a push rod 47 (see Fig. 5). The push rod is operable between guide rollers 48 in an appropriate supporting bracket 65 49. At one end it is provided with a fork

which connects with a complementary crank arm 50, fixedly mounted on the outer end of a short rock shaft 51. The rock shaft 51 is mounted in appropriate bearings and carries an upstanding tappet 52.

The tappet 52 is located within the line of travel of an outstanding lug or the like 53 carried by the fender of the engine. It follows that when the engine comes along, this lug engages the tappet to rocket the shaft 51 75 and actuates the push rod 47. However, a coiled spring 54 surrounds this rod and engages a suitable shoulder carried by the rod at one end while at its opposite end it may engage an adjacent bracket 49 as shown in 80 Fig. 5.

Obviously, the spring serves to return the parts of this mechanism to normal position ready for operation. The operation of the 85 device is as follows.

Assuming that the train approaches the trip mechanism, the outstanding part 53 of the fender of the train will engage the tappet 52 and thus trip the mechanism. It follows that the shaft 51 oscillates in a direction to 90 exert a forward thrust upon the push rod 47 through the medium of the crank arm 50. As this push rod 47 is connected with the aforesaid rockshaft 27 thru the crank arm 46, the gate is allowed to drop down by gravity, and 95 this is because the rotation of the rock shaft 27 brings one of the trip fingers 25 or 26 into play, thus releasing the latch 23.

As the gate is lowered to operative position to provide a barrier, across the highway, the 100 signalling lens 30 which is red, is brought into view. As the gate drops down, the free end portions of the bars 16 and 17 swing into the appropriate guides 14 and 15 as shown in Figs. 6 and 9. Now, the gate can be returned 105 to elevated position either by the manual means, heretofore described, or the electrical contrivance.

It is thought that by considering the detailed description in connection with the accompanying drawings, a clear understanding 110 of the invention will be had. Therefore, a more lengthy description is believed unnecessary.

Having thus described my invention, what 115 I claim as new is:—

1. In a highway crossing gate of the class described, a gravity lowered gate, a retention means cooperable with the gate to hold the gate in an elevated position, and train actuated trip mechanism cooperable with said retention means.

2. In a highway crossing gate of the class described, a gravity lowered gate, retention means cooperable with the gate to hold the gate in an elevated position, and train actuated trip mechanism cooperable with said retention means, together with visible signalling means simultaneously actuated by said gate.

3. In a highway gate crossing structure of the class described, a gate adapted to be lowered to barrier forming relation thru the medium of gravity, a latch for holding the gate in elevated position, trip fingers pivotally mounted and cooperable with said latch for releasing it, and train controlled trip mechanism for actuating said trip fingers.
4. In a highway crossing gate structure of the class described, a post, a gate swingably mounted on said post and adapted to be lowered to operative position by gravity, a spring pressed latch for holding said gate in elevated position, a rock shaft mounted on said post, trip fingers carried by said rock shaft and cooperable with said latch, train controlled trip mechanism for actuating said rock shaft, and means for raising said gate to elevated position.
5. In a highway crossing gate structure of the class described, a post, a gate swingably mounted on said post and adapted to be lowered to operative position by gravity, a spring pressed latch for holding said gate in elevated position, a rock shaft mounted on said post, trip fingers carried by said rock shaft and cooperable with said latch, train controlled trip mechanism for actuating said rock shaft, and means for raising said gate to elevated position.

In testimony whereof I affix my signature.

JOHN ARTHUR ANDERSON.
